AIR BLEED FUEL INJECTOR SYSTEM
Howard E. Brown, Austin, Tex., assignor to the United
States of America as represented by the Secretary of
the Navy

Filed Oct. 26, 1951, Ser. No. 253,401
 3 Claims. (Cl. 60—39.74)

This invention relates to fuel injectors, and more particularly to injectors for feeding liquid fuel into an air stream to provide an atomized combustible mixture for use in aerial missiles of the ramjet type and similar aerial vehicles.

Heretofore difficulty has sometimes been encountered in securing proper feeding of the fuel in ramjet missiles, because lateral accelerations of the missile caused lateral pressure gradients in the fuel distributing headers or manifolds, whereby, in turn, some of the fuel nozzles received more pressure than others, resulting in non-uniform fuel feeding and consequent uneven burning. This invention is designed to prevent such maldistribution of the fuel by eliminating the header and grouping all the fuel injection nozzles at substantially the same location.

An object of the invention is to provide an improved construction for feeding fuel to the burners of a ramjet.

Another object of the invention is to utilize the air pressure produced by the travel of the vehicle through the atmosphere to feed air into injection tubes to mix with and atomize the liquid fuel that is also fed into said tubes.

Still another object of the invention is to provide a rugged and compact structure of the air and fuel injectors and burners, wherein they are built into struts extending from the inner wall of the ramjet to a central member.

An additional object of the invention is to provide a fuel-injection and burner system which has the operational characteristics of upstream injection even though the injection tubes may point downstream.

Other objects and many of the attendant advantages of this invention will be appreciated readily as the same becomes understood by reference to the following detailed description, when considered in connection with the accompanying drawings, wherein:

FIG. 1 is an axial section through the burner structure of a ramjet missile embodying the invention, with fragments of the ramjet shells being shown, the section being taken along plane 1—1 of FIG. 2, and certain portions being shown in elevation;

FIG. 2 is a front elevation of the burner structure for a ramjet missile, on a smaller scale, the inner and outer shells of the ramjet being shown in cross section;

FIG. 3 is a cross section of a strut along plane 3—3 of FIG. 1, and

FIG. 4 is a similar cross section along the plane 4—4 of FIG. 1.

Referring first to FIGS. 1 and 2, the ramjet has an outer shell 1 and an inner shell 2, thus providing between the shells a space within which customarily certain accessories may be mounted; for example, the fuel storage tank, control mechanism, and other elements, none of which are directly concerned in the present invention. There is located in this space a fuel manifold 3 shown by way of example as a complete ring, encircling the inner shell 2, although the invention is not thereby intended to be limited to this specific form of manifold. The manifold 3 is in communication with the fuel source, which may be connected thereto in any conventional way.

From the manifold 3 a fuel feed pipe 6 extends into each of the struts 4, as best shown in FIG. 2. As arbi-

2

trarily six such struts are here illustrated, there will be the same number of fuel feed pipes 6.

One of these fuel feed pipes 6 is shown in detail in FIG. 1 and it will serve to illustrate all of the fuel feed lines since they are alike. Pipe 6, by means of suitable fittings well known in the art, connects the interior of manifold 3 to the fuel passage 7 in strut 4 so that thereby liquid fuel from the storage tank will be fed into a central cavity 8, whence it is distributed to all the burners, 10 as described hereinafter.

Each strut extends radially inward from the inner shell 2 to a central hub 9 wherein a portion of said cavity 8 is located, and each strut has therein a fuel passage 7 communicating with the cavity, so that any or all of said pipes 15 will keep the cavity 8 supplied with liquid fuel.

A cylindrical fitting 10 is secured to the hub 9 so that the bore 11 of said fitting forms a continuation of the cavity 8 in said hub, and has a number of threaded openings 14 in its wall. The fitting 10, which has a forward 20 closed end 12, may be secured to the hub in any preferred way that provides a tight joint, as by the slightly tapered screw threads 13.

Preferably the threads in openings 14 are also tapered. For example, they may be standard pipe threads, so that 25 a plug 15 may be tightly screwed into each. The plugs 15 have small axial holes therethrough so that each plug may serve as a nozzle to feed liquid fuel radially outward from the fitting 10. Each plug 15 may have a prismatic opening at its outer end to receive a suitable wrench having 30 a correspondingly-shaped end, whereby the plug may be screwed into the fitting 10. As shown, the plugs have hexagonal openings 16 to receive wrenches of the type used for socket-head screws such as the "Allen" type screws.

In the device specifically illustrated, there are eighteen plugs 15, three for each of the six struts, but obviously this is arbitrary and the total number of plugs will vary with the number of struts and the number per strut. Radially aligned with each plug 15 is an injector passage 40 such as 17, 18 and 19. Each injector passage has its inner end, such as 17A, 18A, and 19A, adjacent to an annular air passage 21. The outer ends 17B, 18B, and 19B of each passage 17, 18, and 19 is located at 17C, 18C, and 19C of strut portion 4.

45 A tubular projection or cup 20 extending in the direction of travel of the ramjet, that is, to the left in FIG. 1, as shown by the arrow, surrounds the forward closed end 12 of fitting 10 and defines the annular air passage 21 between itself and said fitting 10. This air passage 21 is closed at 22 at its rear end, but is in communication 50 with the inner end of each of the injector passages 17, 18 and 19. The injector passages are of unequal lengths, the forward one 17 being the longest, the middle one 18 being somewhat shorter and the rearward one 19 being the shortest.

At the outer ends of the respective injector passages are outlets 23, 24 and 25, each formed between the forward portion of the corresponding strut and a separable rear portion 5.

60 A few additional details of the struts and the central hub are given below. In order to keep the thickness of the struts small, enlargements are provided only at their ends as shown at 26, for example, to accommodate the threaded ends of the fuel feed pipes 6.

To keep the separable rear portions 5 in place, alining dowel pins 27, 28 may be provided which will serve also to keep the inner and outer portions of the respective fuel 65 passages 7 in proper alignment in each strut.

70 A rounded forward end portion 12 of the fitting 10 serves to diminish the air friction at the entrance to the cup 20 and a pointed rear end 29 at the center of the

downstream side of the strut hub 9 accomplishes a similar purpose there.

In operation, assuming that the ramjet missile has been launched to proper speed, atmospheric air will flow through the inner casing 2 and some of said air will strike the forward open end of the cup 20, and produce stagnation pressure within the annular space 21. As a consequence, air will escape radially outward through each injector passage 17, 18 and 19. The fuel in cavity 8 is held at a pressure somewhat higher than the air pressure at the same time prevailing in the cup 20, so that jets of fuel will issue from the nozzles in plugs 15, directed axially of said injector passages, thus causing the fuel to become atomized and mixed with the air. Finally the mixture will be discharged through the laterally and rearwardly directed openings 23, 24 and 25, and burned upon reaching the air stream flowing through the ramjet.

Obviously many modifications and variations of the invention are possible in the light of the above teachings. It is therefore to be understood that within the scope of the appended claims, the invention may be practiced otherwise than as specifically described.

What is claimed is:

1. A fuel distributing device for an aerial vehicle of the ramjet type, comprising a hollow hub within said ramjet vehicle, a plurality of struts extending outwardly from said hub to the wall of said ramjet vehicle, said struts having passageways therein communicating with the interior of the hub and a fuel supply manifold connected to the outer ends of said passageways, said hub having a plurality of apertures formed therein for directing fuel outwardly from the hub in jet streams, and means for receiving said jet streams and for mixing air therewith and for directing the air-fuel mixture radially to the longitudinal axis of the ramjet, whereby the flow of fuel from the hub is substantially unaffected by lateral accelerations of the ramjet.

2. An aerial vehicle of the fuel distributing device for a ramjet type, comprising, a hollow hub located substan-

tially axially of said ramjet vehicle, a plurality of struts extending radially outward from said hub to the wall of said ramjet vehicle, said struts having passageways therein communicating with the interior of said hub and a fuel supply manifold connected to the outer ends of said passageways, said hub having a plurality of apertures formed therein for directing fuel outwardly from the hub in jet streams, and means for receiving said jet streams and for mixing air therewith and for directing the air-fuel mixture radially to the longitudinal axis of the ramjet, whereby the flow of fuel from the hub is substantially unaffected by lateral accelerations of the ramjet.

3. A fuel distributing device for an aerial vehicle of the ramjet type, comprising, an annular fuel manifold adjacent the wall of said ramjet vehicle, a centrally located hollow hub, a plurality of struts located between said hub and the wall of the ramjet, each strut being divided into at least two portions, a portion of each strut being integral with the hub and extending outwardly substantially to the wall of said ramjet, the complementary portion being separable therefrom and having a conduit therein communicating with said manifold, means for holding said hub strut portions and said complementary strut portions together to form a rigid unit, said hub having bores therein forming continuations of said conduits, said hub having a plurality of apertures formed therein for directing fuel outwardly from the hub in jet streams, and means for receiving said jet streams and for mixing air therewith and for directing the air fuel mixtures radially to the longitudinal axis of the ramjet.
